(57) **CLAIM**

The ornamental design for a food tray, as shown and described.

DESCRIPTION

FIG. 1 is a perspective view of a food tray showing my new design;

FIG. 2 is a front end elevation of the food tray of FIG. 1;

FIG. 3 is a rear end elevation of the food tray of FIG. 1;

FIG. 4 is a left side elevation of the food tray of FIG. 1;

FIG. 5 is a right side elevation of the food tray of FIG. 1;

FIG. 6 is a top plan view of the food tray of FIG. 1; and,

FIG. 7 is a bottom plan view of the food tray of FIG. 1.

In the drawings, the broken lines are included for the purpose of illustrating portions of the food tray that form no part of the claimed design.
